ATTORNEY.

UNITED STATES PATENT OFFICE.

JOSEPH B. HILL, OF PHILADELPHIA, PENNSYLVANIA, ASSIGNOR TO THE IMPERIAL CUT GLASS COMPANY, OF PENNSYLVANIA.

DESIGN FOR A GLASS DISH.

SPECIFICATION forming part of Design No. 26,396, dated December 15, 1896.

Application filed March 28, 1896. Serial No. 585,289. Term of patent 7 years.

To all whom it may concern:

Be it known that I, JOSEPH B. HILL, a subject of the Queen of Great Britain, residing in the city and county of Philadelphia, State 5 of Pennsylvania, have invented and produced a new and original Design for a Glass Dish, of which the following is a specification, reference being had to the accompanying drawings, forming part thereof.

10 The leading feature of my design for a glass dish is the representation of a group of stars inclosing a group of stars of smaller dimensions, alternating with checkered fields, having borders with checkered corners, forming 15 a rim around a central star-shaped figure, having radiating rays alternating with checkered squares of decreasing dimensions toward the center of said figure.

Figure 1 represents a plan view of a dish 20 embodying my design. Fig. 2 represents a diametrical vertical section thereof, omitting the representations on the inner face thereof.

In the drawings, A designates a dish on 25 which is the representation of stars B, which are grouped one on the other and inclose the representation of stars C of smaller size, which are also grouped one on the other.

D designates a representation of a check-

ered field, which is inclosed by the representation of a frame E, with checker-work F at 30 the corners thereof.

The stars B C are inclosed by a frame which joins the frame E. Between the frames is a fan-shaped figure, it being noticed that the stars B C, the checkered field D, the frame 35 E, with checkered corners F, constitute the rim or border of the dish.

G designates the representation of radiating rays, between which are representations of checkered squares H, which decrease in 40 size toward the center of the dish.

The border of the rays G and squares H are the outlines of a star-shaped figure J, whose points K project between the groups of stars B and the frames E of the field D. 45

The radiating rays G, the checkered squares H, of decreasing sizes alternately between said rays, forming together the star-shaped figure J, constitute the bottom of the dish.

What I claim is—

25 The design for a dish, substantially as described and shown.

JOSEPH B. HILL.
